CLAIM

We claim a new ornamental design for a gripper for auto-injector needle shield, as shown and described.

DESCRIPTION

FIG. 1 is a top, front, left perspective view of a gripper for auto-injector needle shield, showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

1 Claim, 7 Drawing Sheets
